UNITED STATES PATENT OFFICE.

THOMAS H. SEELY, OF BOSTON, MASSACHUSETTS, ASSIGNEE, BY MESNE ASSIGNMENTS,
TO UNITED SHOE MACHINERY CORPORATION, OF PATERSON, NEW JERSEY, A COR-
PORATION OF NEW JERSEY.

WAX-THREAD SEWING-MACHINE.

1,302,597.

Specification of Letters Patent.

Patented May 6, 1919.

Application filed January 25, 1915. Serial No. 4,269.

To all whom it may concern:

Be it known that I, THOMAS H. SEELY, a citizen of the United States, residing at Dorchester, Boston, in the county of Suffolk 5 and State of Massachusetts, have invented certain new and useful Improvements in Wax-Thread Sewing-Machines; and I do hereby declare the following to be a full, clear, and exact description of the invention, 10 such as will enable others skilled in the art to which it appertains to make and use the same.

This invention relates to wax thread sewing machines and more particularly to inclosing casings or hoods for such machines. 15

In a wax thread sewing machine the wax is ordinarily applied to the needle thread by conducting the thread leading from the supply through a receptacle or pot containing 20 melted wax. The wax pot is usually located at some distance from the sewing point and the thread after emerging from the wax pot passes over a series of thread handling devices before it reaches the work. It is practically essential in sewing with wax thread 25 that the thread be kept warm from the time when it emerges from the wax pot until it reaches the work in order that the wax which is applied to the thread may be in proper condition when the thread is incorporated in the seam. In a lock-stitch, wax 30 thread sewing machine the wax is usually applied to the bobbin thread while the bobbin is being wound, the bobbin full of waxed thread being inserted in the rotary hook or shuttle prior to the beginning of the sewing operation. In order to keep the needle thread warm from the time that it leaves the wax pot until it reaches the work, heating 35 devices are usually provided for heating the parts of a wax thread sewing machine, particularly the parts adjacent the path of the thread from the wax pot to the work. In a lock-stitch, wax thread sewing machine 40 provision is also made for heating the rotary hook or shuttle so as to reduce the wax on the bobbin thread to the proper condition. It is often difficult to keep the parts of a wax thread machine properly heated, especially 45 in cold weather when the temperature of the stitching room in the shoe factory falls to a relatively low point. In summer when the windows of the stitching room are 50

opened drafts of air striking the machine chill the wax on the thread, causing a great 55 deal of trouble. The chilling of the wax on the thread causes frequent breakage of the thread and thus results in a waste of thread and also in a considerable loss of time since it is necessary for the operator to rethread 60 the machine each time that the thread is broken.

The primary object of the present invention is to provide an improved inclosing casing or hood for wax thread sewing machines which will effectually retain the heat of the machine and protect the machine from air currents and which is so constructed that access may readily be had to the parts of the machine within the casing. 65 With this and other objects in view the features of the invention consist of certain novel constructions, arrangements and combinations hereinafter described and particularly pointed out in the claims, the advantages of which will be obvious to those skilled in the art. 70

The accompanying drawings illustrate the invention in its preferred form and the novel features thereof will be readily understood 80 from an inspection of the drawings and the following detailed description of the same.

In the drawing Figure 1 is a view in front elevation of a wax thread sewing machine with applicant's inclosing casing or hood applied thereto. Fig. 2 is a central sectional view of the inclosing casing showing the movable sections or doors of the casing in normal or closed positions, and outlining certain parts of the sewing machine in dot 85 and dash lines. Fig. 3 is a view similar to Fig. 2 showing the movable sections or doors of the casing in open positions. Fig. 4 is a detail sectional view of a portion of the casing taken substantially on the line 4-4 of 90 Fig. 1 and illustrating certain parts of the machine in dot and dash lines. Fig. 5 is a detail sectional view taken substantially on the line 5-5 of Fig. 2 and illustrating the parts of the machine in full lines and Fig. 100 6 is a detail view illustrating particularly the rear section of the casing.

The invention is illustrated in the drawings as applied to a lock-stitch, curved hook needle sewing machine for sewing outsoles 105 of welted shoes having substantially the

same construction as the machine illustrated in Ashworth application, Serial No. 769,566, filed May 24, 1913. It is to be understood, however, that the invention is not limited 5 to this particular type of machine but that certain features thereof may be applied with advantage to other machines.

The sewing machine illustrated in the drawing with the inclosing casing applied 10 thereto comprises an oscillating curved hook needle 2, an awl 4, a rotary hook or shuttle 6, a work support 8, and a presser-foot 10. The presser-foot is mounted on a forwardly extending arm of a lever 12, pivoted at 14 on 15 the frame of the machine. In the machine illustrated, the presser-foot during each cycle of operations starting at a point just after the work has been fed, is moved into engagement with the work, is pressed against the 20 work with a yielding pressure, and is then depressed positively a predetermined distance and is locked in depressed position during the formation of the stitch after which it is lifted from the work to permit 25 the work to be fed. The mechanism for actuating the presser-foot in this manner need not be described in this application. In order that the presser-foot may be unlocked and lifted at a time when it is normally locked in work engaging position a 30 lever 16 is pivotally mounted coaxially with the presser-foot lever 12 and is provided with a lateral projection 18 arranged to engage the rear side of the downwardly projecting arm of the lever 12. The upper end of the lever 16 is connected by a link 20 with an arm 22 of a lever 22-24 mounted on a shaft 26. The other arm 24, of the lever is arranged to act on the locking mechanism 35 40 to unlock the presser-foot before it is lifted as fully described in the Ashworth application referred to above. The presser-foot is unlocked and lifted manually by grasping the upper end of the lever 16 and swinging 45 the same toward the rear of the machine.

The bobbin is inserted in a chamber in a cylindrical thread case which is mounted in an opening in the rotary hook 6. In order to enable the bobbin to be easily removed 50 from the bobbin case without removing the bobbin case from the rotary hook a bobbin ejector 28 is mounted upon a shaft 30 and is provided with a forwardly extending operating end adapted to enter an opening in the 55 rear face of the bobbin case and engage the bobbin as it lies in the bobbin case to thrust the same from the bobbin case. An arm 32 is fixed to the shaft 30 by which the bobbin ejector may be operated manually in a 60 manner hereinafter described. The bobbin ejector is normally held in inoperative position by a coiled spring 32a.

The machine comprises a wax pot 34 for applying melted wax to the needle thread.

65 The course of the thread as it passes from

the wax pot to the sewing point is shown clearly in Figs. 2 and 3. The thread passes from the supply down into the wax pot and as it emerges from the pot it extends through a stripping device not shown and over a 70 thread truck 36 from which it passes forwardly through an opening or bore 38 in the frame of the machine. After emerging from the bore 38 the thread extends about the tension wheel 40 through the guide eyes of the 75 pull-off device 42, about the thread truck 44 of the thread locking device, over the thread truck 46 of the auxiliary take-up, about the thread truck 48 of the main take-up, from the main take-up to the eye of looper 50 and 80 thence to the work,

In the machine illustrated in the drawing, devices are provided for heating certain parts of the machine by steam. In order to heat the shuttle and certain adjacent parts 85 of the machine the bracket above the shuttle is provided with a steam chamber 52 connected with a steam inlet pipe 54. The tension device take-up and adjacent parts are heated by means of a steam chamber 56 90 formed in the portion of the frame upon which certain of these parts are mounted and connected with the steam chamber 52 by means of a steam pipe 58. The exhaust pipe 60 from the steam chamber 56 is connected at its rear end with a U tube extending down into the wax pot which keeps the wax in the pot in a fluid condition along the path of the thread. The above construction and arrangement of the machine heating devices is not essential and any other suitable and convenient means for heating the machine may 95 be employed.

The casing for inclosing the head of the machine comprises a top section or cover 62, 105 two front sections 64 and 66 covering substantially the whole front portion of the machine and a rear section 68 covering the parts of the machine at the rear of the top section. The forward portion of the top section 62 is 110 secured to the frame by means of a screw 70 located substantially at the center thereof and the rear portion of said section is secured by means of screws 72 to a bracket 72a fixed to the frame of the machine.

The section 64 of the casing consists of a movable closure or door pivoted to the frame of the machine upon trunnions 74 mounted in split clamps 76 on the frame and secured in place by means of clamping screws 78. This manner of mounting the section 64 of the casing permits said section to swing forwardly and downwardly as shown in Fig. 3 to give access to the parts of the machine covered by this section of the casing. To 120 limit the distance which the section 64 can be swung and to support the section when in open position a link 80 having at its upper end a slot 82 is mounted upon a rod 84 passing through the slot 82, the other end of 125 130

the link having a slot 86 in which engages a stud 88 fixed in the section 64 of the casing. When the section 64 of the casing is closed the rod 84 and stud 88 occupy the inner ends respectively of the slot 82 and the slot 86 in the link as shown in Fig. 2. As the section 64 of the casing is opened the link 80 slides longitudinally along the rod 84 and the stud 88 moves toward the outer end 10 of the slot 86 and the swinging movement of the section 64 is limited by the engagement of the rod and the stud with the ends of the respective slots in the link. With the section 64 in open position as shown in Fig. 15 the operator can gain access to any of the parts of the machine which are normally covered by this section of the casing to adjust or oil the same or for any other purpose. To prevent the section 64 from swinging freely from closed to open position, which might cause the rod 84 and the stud 88 to bring up against the ends of the slots in the link 80 with considerable force and cause breakage of the parts, friction washers 20 90 are mounted on the rod 84 on each side of the link 80 and a coiled spring 92 is interposed between the outer of said washers and a nut 94 threaded on the rod. This spring causes the washers 90 to frictionally 25 engage both sides of the link and act as a brake on the link to retard the downward swinging movement of the section 64. The section 64 of the casing is held in closed position by means of a clamping bolt 96 engaging in a slot 98 in the section 64 and threaded into the section 62 of the casing. In opening the section 64 the bolt 96 is partially unscrewed as shown in Fig. 3, the slot 98 in the section 64 enabling said section 30 to be swung to open position without entirely unscrewing the bolt from the section 62. The upper edge of the section 64 at each side of the clamping bolt 96 is supported by means of adjustable abutment screws 100 35 threaded into the top section of the casing. 40

The top section 62 of the casing is provided with a shoulder 102 and this shoulder and the upper edge of the front section 64 are preferably formed to fit closely together 45 when the sections 62 and 64 are properly located. To enable the shoulder 102 to be fitted accurately to the upper edge of the front section, the top section is adjustable angularly. The angular adjustment of the 50 top section is affected by means of abutment screws 104 threaded into the rear portion of the top section and arranged to engage the bracket 72^a at their lower ends. By loosening the screws 70 and 72 and adjusting 55 the abutment screws 104 the top section may be given the proper angular adjustment to fit the bolt 102 to the upper edge of the section 64.

The section 64 of the casing may be adjusted laterally of the machine by loosening the

clamping screws 78 and adjusting the trunnions 74 longitudinally. The section 64 may be bodily removed from the machine by loosening the right hand clamping screw 78 and drawing out the trunnion 74 to disengage it from the section 64. This leaves the section 64 free to be manipulated to disengage the stud 88 from the slot 86 in the link 80 and then to disengage the left-hand trunnion from said section. In order that 75 the right-hand trunnion 74 may be more easily manipulated by the operator a pin 74^a is mounted therein.

The upper portion of the lower front section 66 of the casing fits into a recess in the upper front section 64 as shown particularly in Figs. 1 and 2. The upper front section and the lower front section are cut away respectively at 106 and 108 so as to form an opening at the sewing point for the 80 presentation of the shoe to the machine. The opening formed by cutting away the two front sections of the hood at the sewing point is relatively small as compared with the size of the shoe and in order to permit 85 the shoe to be manipulated to present the different portions thereof to the sewing mechanism as the point of operation is transferred about the shoe, the lower front section of the casing is constructed to hug the 90 machine closely, particularly at points in front of and to the rear of the point of operation as shown in Fig. 5. The lower front section 66 of the casing covers particularly 95 the parts of the thread handling mechanism 100 at the front of the machine over which the thread passes on its way from the wax pot to the sewing point and assists in maintaining these parts in a properly heated condition. To permit the operator to gain access to the parts of the machine covered by the lower front section this section of the casing is mounted so that it may be swung from closed position to open position as shown in Fig. 3. To this end the section 66 105 is secured by a clamping screw 110 to an arm 112 pivoted at 114 to the frame. The upper edge of the section 66 and the adjoining lower edge of the upper front section 64 are preferably formed so that these sections 110 fit closely together when they are located in proper relative positions. In order to enable the adjacent edges of the two front sections to be fitted together accurately, the lower section 66 is adjustable both vertically 115 and angularly. The angular adjustment of the section 66 is effected by loosening the clamping screw 110 and swinging said section about the clamping screw to locate it in proper angular position. To permit the 120 vertical adjustment of the section 66 the arm 112 is formed with a slot 116 through which the clamping screw 110 passes.

The rear section 68 of the casing covering the parts of the machine below and to the 130

rear of the top section 62 is pivoted upon the shaft 118 mounted in arms 120 of a bracket 122 fixed to the frame of the machine, the section 68 being formed with 5 downwardly projecting arms or lugs 124 through which the shaft 118 passes. This manner of mounting the section 68 enables this section to be swung rearwardly and downwardly from closed position as shown 10 in Fig. 3 to expose the parts of the machine covered by the same. The opening movement of the section 68 is limited by the engagement of an arm 126 formed on said section with an abutment 128 on the frame of 15 the machine. The position of the section 68 longitudinally of the shaft 118 is determined by fixed collars 130 mounted on the shaft and engaging the inner faces of the arms 124, these collars being held in place 20 on the shaft by set screws 132. The section 68 may be adjusted longitudinally of the shaft 118 to fit it properly to the machine by loosening the set screws 132 which hold the collars 130 in place on the shaft and adjusting the collars along the shaft. 25

When the bobbin thread is exhausted it is necessary for the operator to remove the bobbin from the bobbin case and replace it with a full bobbin. The upper front section 30 of the casing covers the usual bobbin ejector lever so that the operator cannot get at this lever without opening this section. In order that the operator may be able to actuate the bobbin ejector lever without 35 opening the casing a shaft 134 is mounted in bearings in the section 64 of the casing, this shaft extending through from the exterior to the interior of the section 64. An arm 136 is fixed to the end of the shaft 134 40 within the section 64 and carries at its upper end an adjustable abutment screw 138 to engage the arm 32 of the bobbin ejector lever. An operating arm 140 is fixed to the end of the shaft 134 outside of the section 45 64. To actuate the bobbin ejector lever to eject the bobbin the operator grasps the arm 140 and swings the same toward the rear of the machine.

It is often necessary for the operator to 50 left the presser-foot manually in introducing or removing the work or in adjusting the work in the machine. The upper front section of the casing incloses the hand lever 55 16 so that the operator cannot reach this lever when the casing is closed. To obviate this difficulty an arm 142 (see Fig. 4) is fixed to the inner end of a shaft 144 mounted in bearings in the upper front section 64 of the casing, the upper end of the arm 142 60 being constructed to engage the hand lever 16 as shown in Fig. 4. The shaft 144 extends through the section 64 of the casing to the outside thereof and an operating arm 146 is fixed to the outer end of this shaft. 65 The presser-foot may be lifted by the oper-

ator by grasping the operating arm 146 and swinging same toward the rear of the machine.

The inclosing casing above described is so constructed that it effectively retains the 70 heat of the machine with the result that both the needle thread and the shuttle thread reach the work with the wax which has been applied to the threads in condition to make a satisfactory tight seam. In wax thread 75 sewing machines which are not provided with inclosing casings the frequent breakage of the thread due to chilling of the wax on the thread before it reaches the work causes a great deal of trouble. When starting 80 such machines it is often necessary to pull out a foot or more of thread in order to put the machine in condition to run. These disadvantages are obviated by the use 85 of the applicant's inclosing casing.

In addition to retaining the heat of the machine the casing has other important advantages. The greater part of the moving elements of the machine at the front thereof is covered by the casing so that it prevents 90 oil from being thrown from the machine into the eyes of the operator or on to the work. The rapidly moving parts in the line of the operator's vision are for the most part covered by the casing so that the eyes do not become 95 tired from watching these parts as is the case in machines where these parts are not inclosed. The casing also acts as a guard for the parts of the machine to prevent contact of the shoe therewith during the sewing 100 operation.

Having explained the nature and scope of the invention and having specifically described a machine embodying the invention in its preferred form what is claimed is:— 105

1. A wax thread sewing machine for sewing outsoles to the welts of welted shoes, having, in combination, stitch forming devices including a curved hook needle, a work support, a presser foot, means for heating 110 the machine, an inclosing casing for the machine comprising a top section, a series of hollow sections inclosing substantially the whole front of the machine above, below, and at each side of the sewing point, having a 115 relatively small opening through which the stitch forming devices, work support and presser foot project beyond the contour of the casing into position for the presentation of a shoe thereto, and shaped to hug the machine closely adjacent the opening to permit the manipulation of the shoe outside of the casing so as to present the different parts of the outsole and welt in proper position to the 120 stitch forming devices as the point of operation is transferred about the shoe, and means for movably supporting the front sections of the casing to enable these sections to be 125 opened to expose the parts of the machine covered thereby. 130

2. A wax thread sewing machine for sewing outsoles to the welts of welted shoes, having, in combination, stitch forming devices including a curved hook needle, a work support, a presser foot, a wax receptacle located at the rear of the machine, a tube for inclosing the thread in its passage from the rear to the front of the machine, a series of thread handling devices located at the front 10 of the machine intermediate said tube and the needle, a casing for the machine inclosing the top of the machine and substantially the whole front of the machine above, below and at each side of the sewing point, having a 15 relatively small opening through which the stitch forming devices, work support and presser foot project beyond the contour of the casing into position for the presentation of a shoe thereto and shaped to hug the machine closely adjacent the opening to permit 20 the manipulation of the shoe outside the casing so as to present the various parts of the outsole and welt in proper position to the stitch forming devices as the point of operation is transferred about the shoe, the casing comprising a section inclosing said thread 25 handling devices, and means for movably supporting said section to enable the same to be opened to expose said thread handling 30 devices.

3. A wax thread sewing machine having in combination stitch forming devices, a work support, a presser-foot, an inclosing casing for the machine and manually operable presser-foot lifting mechanism mounted on the casing and extending from the interior to the exterior of the casing.

4. A wax thread, lock-stitch sewing machine having in combination stitch forming devices, including a needle, a bobbin, a bobbin container, a bobbin ejector, an inclosing casing for the machine and manually operable mechanism for actuating the bobbin ejector mounted on the casing and extending 45 from the interior to the exterior of the casing.

5. A wax thread sewing machine having in combination stitch forming devices, an inclosing casing for the machine covering the top and substantially the whole front of the 50 machine above, below and at each side of the sewing point, having a relatively small opening at the sewing point through which the stitch forming devices project, and constructed to hug the machine closely adjacent 55 the opening to permit the manipulation of the shoe outside the casing, said casing comprising a series of independent sections and means whereby certain of said sections may be relatively adjusted to fit them together at 60 their adjoining edges.

6. A wax thread sewing machine having in combination stitch forming devices, an inclosing casing for the head of the machine comprising a series of movable sections one 65 of which is hinged to swing downwardly to

give access to the parts of the machine within the casing, a link connection between said hinged section and the frame to limit the opening movement thereof, and a brake applied to said connection. 70

7. A wax thread sewing machine, having, in combination, stitch forming devices, an inclosing casing for the machine comprising a top section, an upper front section having a recess, a lower front section fitting into said recess and having its edge in abutting relation to the edge of the upper front section along the recess, and means whereby the lower front section may be adjusted angularly and vertically to fit it to the abutting 75 edge of the upper front section. 80

8. A wax thread sewing machine for sewing outsoles to the welts of welted shoes, having, in combination, stitch forming devices including a curved hook needle, a work support, a presser foot, an inclosing casing for the machine comprising a fixed top section, a hollow rear section fitted at its upper edge to the top section, and covering the parts of the machine at the rear of the top section, two hollow front sections fitted together at their adjoining edges covering substantially the whole front of the machine, having a relatively small opening through which the stitch forming devices, 90 work support and presser foot project beyond the contour of the casing into position for the presentation of a shoe thereto and shaped to hug the machine closely adjacent the opening to permit the manipulation of the shoe outside of the casing so as to present the different parts of the outsole and welt in proper position to the stitch forming devices as the point of operation is transferred about the shoe, and means for 95 movably supporting the last three sections of the casing to enable these sections to be opened to expose the parts of the machine covered thereby. 100

9. A wax thread sewing machine for sewing outsoles to the welts of welted shoes, having, in combination, stitch forming devices including a curved hook needle, a work support, a presser foot, an inclosing casing for the machine comprising a fixed top section, a series of movable hollow sections covering the machine at the rear of the top section, and substantially the whole front of the machine above, below, and at each side of the sewing point, having a relatively small opening through which the stitch forming devices, work support and presser foot project beyond the contour of the casing into position for the presentation of a shoe thereto, and shaped to hug the 115 machine closely adjacent the opening to permit the manipulation of the shoe outside of the casing so as to present the different parts of the outsole and welt in proper position to the stitch forming devices as the 120 125 130

point of operation is transferred about the shoe, and means for pivotally supporting each of said movable sections adjacent its lower end to permit it to be swung outwardly and downwardly from closed to open position to expose the parts of the machine covered thereby.

10. A waxed thread sewing machine for sewing outsoles to the welts of welted shoes, having, in combination, stitch forming devices including a curved hook needle, a work support, a presser foot, an inclosing casing for the machine comprising a fixed top section, a hollow rear section fitted at its upper 5 edge to the top section and pivoted adjacent its lower end to swing rearwardly and downwardly from closed to open position, and two hollow front sections covering substantially the whole front of the machine, 15 having a relatively small opening through which the stitch forming devices, work support and presser foot project beyond the contour of the casing into position for the presentation of a shoe thereto, and shaped to 20 hug the machine closely adjacent the opening to permit the manipulation of the shoe outside of the casing so as to present the different parts of the outsole and welt in proper position to the stitch forming devices, 25 as the point of operation is transferred about the shoe, and means for pivotally supporting each of said front sections to swing forwardly and downwardly from closed to open position to expose the parts 30 of the machine covered thereby.

11. A wax thread sewing machine, having, in combination, stitch forming devices, an inclosing casing for the machine comprising a fixed top section, a movable rear 40 section, and movable upper and lower front sections covering substantially the whole front of the machine above, below and at each side of the sewing point, and means whereby the rear and upper front sections 45 may be adjusted laterally, the top section may be adjusted angularly, and the lower front section may be adjusted vertically and angularly to fit the sections together.

12. A wax thread sewing machine having 50 in combination stitch forming devices, an inclosing casing for the machine comprising a series of independent sections and means whereby one of said sections may be adjusted linearly and angularly.

55. 13. A wax thread sewing machine, having, in combination, stitch forming devices, an inclosing casing for the machine comprising a series of independent sections, two alined pivot pins for supporting the opposite ends of one of said sections, and split clamps for removably clamping the supporting pivots in position whereby the pivot pins may be adjusted to adjust the section laterally of the machine, or one of the pins 60

may be adjusted to enable the section to be 65 removed bodily from the machine.

14. A wax thread sewing machine, having in combination, stitch forming devices, a work support, a presser foot, an inclosing casing for the machine, a rock shaft mounted on 70 the casing and extending from the exterior to the interior thereof, an arm mounted on the end of the rock shaft within the casing for lifting the presser foot, and an operating arm mounted on the end of said rock 75 shaft outside of the casing.

15. A wax thread lock stitch sewing machine, having, in combination, stitch forming devices including a needle, a bobbin, a bobbin container, an inclosing casing for 80 the machine, a rock shaft mounted on the casing and extending from the exterior to the interior thereof, a bobbin ejecting arm mounted on the end of the rock shaft within the casing, and an operating arm mounted 85 on the end of the rock shaft outside of the casing.

16. A wax thread sewing machine for sewing outsoles to the welts of welted shoes, having, in combination, stitch forming devices including a curved hook needle, a work support, a presser foot, machine heating devices, an inclosing casing for the head of the machine comprising a top section, a hollow upper front section fitted to the top section at its upper edge, a hollow lower front section fitted at its upper edge to the upper front section, and means for movably supporting the two front sections to enable these sections to be opened to expose the parts of 90 the machine covered thereby, the two front sections being shaped to hug the machine closely above, at each side of, and below the sewing point to permit the manipulation of the shoe outside of the casing so as to 95 present the different parts of the outsole and welt in proper position to the stitch forming devices as the point of operation is transferred about the shoe, and having a relatively small opening at the sewing point 100 through which the stitch forming devices, work support and presser foot project beyond the contour of the casing into position 105 for the presentation of a shoe thereto.

17. A wax thread sewing machine for 115 sewing outsoles to the welts of welted shoes, having, in combination, stitch forming devices including a curved hook needle, a work support, a presser foot, machine heating devices, an inclosing casing for the head 120 of the machine comprising a top section, a hollow upper front section fitted to the top section at its upper edge, means for pivotally supporting the upper front section adjacent its lower end to swing forwardly and 125 downwardly from closed to open position, means for limiting the opening movement of the upper front section, a hollow lower

front section fitted at its upper edge to the upper front section, and means for pivotally supporting the lower front section adjacent its lower end to swing forwardly and down-
wardly from closed to open position, the two front sections being shaped to hug the machine closely above, at each side of, and below the sewing point to permit the manipulation of the shoe outside of the casing so as to present the different parts of the out-
sole and welt in proper position to the stitch

forming devices as the point of operation is transferred about the shoe, and having a relatively small opening at the sewing point through which the stitch forming devices, ¹⁵ work support and presser foot project into position for the presentation of a shoe thereto.
